G. HAMMOND

FIREARM

Original Filed July 20, 1917

UNITED STATES PATENT OFFICE.

GRANT HAMMOND, OF NEW HAVEN, CONNECTICUT, ASSIGNOR OF ONE-THIRD TO
ALVA C. WASHBURN, OF PITTSFIELD, MASSACHUSETTS, AND ONE-THIRD TO
FREDERICK G. CRANE, OF DALTON, MASSACHUSETTS.

FIREARM.

Application filed July 20, 1917, Serial No. 181,855. Renewed April 12, 1923.

To all whom it may concern:

Be it known that I, GRANT HAMMOND, a citizen of the United States, and a resident of New Haven, in the county of New Haven and State of Connecticut, have invented a new and Improved Firearm, of which the following is a specification.

My invention relates more especially to the class of firearms that are supported upon the person when being fired and more especially to those that are held in the hand when being so fired, and an object of my invention, among others, is to provide means for automatically operating such a firearm, which means shall be particularly efficient in action; and a further object of the invention is to provide a simplified construction that will enable the parts to be readily and quickly produced.

One form of firearm embodying my invention, and in the construction and use of which the objects herein set out, as well as others, may be attained, is illustrated in the accompanying drawings, in which—

Figure 1 is a view in side elevation of a fire arm embodying my invention with parts broken away to show construction.

Figure 2 is a view in side elevation of a portion of the rear part of my improved firearm, showing the side opposite to that illustrated in Figure 1, and with parts broken away to show construction.

Figure 3 is a rear end view of my improved firearm.

Figure 4 is a bottom view of the receiver.

Figure 5 is a top plan view of the frame.

Figure 6 is a detail view in cross section through the upper part of the device on plane denoted by dotted line 6—6 of Figure 1.

Figure 7 is a detail view in cross section through the device on plane denoted by dotted line 7—7 of Figure 1.

Figure 8 is a detail view in cross section through the breech-bolt showing the manner of securing the breech-bolt stop in place.

In the accompanying drawings the numeral 10 denotes the frame of my improved gun that may be of any desired form and material, the lower end constituting the handle of the firearm having a magazine chamber 11 of any usual form and construction that extends into a receiver to be hereinafter described and within which chamber a maga-

zine (not shown) may be located. The 55 forward upper end of the frame has a trigger guard 12 formed thereon and the upper rear end of the frame has an extension 13 to receive parts of the firing mechanism. An opening 14 extends from the magazine 60 chamber into the opening within the trigger guard through which a trigger bar 15, to be more particularly hereinafter described, extends, the bar being pivotally connected at its front end with a trigger 16 pivotally 65 secured to the frame and normally forced forward as by a trigger spring 17.

A hammer 18 is pivotally mounted in the extension 13, this hammer being of any suitable construction and having a hammer actuating plunger 19 located in a well 20 in the extension 13, a hammer actuating spring 21 being located in the bottom of the well and thrusting against the plunger to force it against the hammer and thereby force the 75 hammer forward for firing action. A sear 22 is pivotally mounted in a sear slot 23 in the upper edge of the frame at the back end thereof, a spring located forward of the pivot of the sear tending to move the sear to 80 engage a notch formed in the hammer in the usual manner. The sear is secured to a sear shaft 24 preferably of angular shape as to that part located within the sear, and this shaft has a sear actuating finger 25 85 projecting radially therefrom to be engaged by the trigger bar in a manner to be hereinafter set forth.

The frame has a hole 26 extending from its upper edge into the opening within the 90 trigger guard, the upper end of the hole being enlarged to contain a receiver stop and lock 27, and also a stop actuating spring 28 surrounding the shank 29 of said stop, the shank terminating in a lock actuating head 95 30 within the trigger guard by means of which the stop may be disengaged from the receiver. A groove 31 in the upper end of the frame extends from the front edge thereof to contain a receiver returning 100 spring, to be hereinafter described. A groove 32 is also located in the upper end of the frame and extends into the magazine opening, this groove being for the purpose of receiving a breech-bolt locking dog to be 105 hereinafter described.

A receiver 33 is removably secured to the upper edge of the frame as by means of

5 lips 34 on the lower edge of the receiver entering grooves 35 extending along opposite sides of the upper end of the frame, this end of the frame in fact being T-shape in cross section as shown in Figure 3 of the drawings, and thus providing lips on each of the parts (frame and receiver) entering grooves in the other part, in a manner common to devices of this class. The receiver has in its under 10 surface, near its front end, a controlling slot 36 that has a retaining recess 37 at one end, said slot and recess being formed to receive the upper end of the receiver stop and lock 27 hereinbefore mentioned. A receiver re- 15 turning spring 38 is located in a chamber formed by the groove 31 and closed at its front end by a lip 39 extending downwardly from the front end of the receiver into the groove 31.

20 A hole of uniform diameter extends completely through the receiver from its front to its back end, a barrel 40 being secured in the front end of this hole in any suitable manner, and the remainder of the hole con- 25 stituting a breech-bolt chamber 41. A breech- bolt unlocking dog 42 is pivotally mounted in a slot 43 cut through the bottom of the receiver opposite the groove 32 in the upper surface of the frame so that said dog is par- 30 tially located in said groove. A hole 44 for a breech-bolt lock, to be hereinafter described, also extends through the bottom of the receiver and preferably cuts into the slot 43. A groove 45 extends lengthwise along the 35 breech-bolt chamber in the top thereof to form part of a breech-bolt actuating spring chamber for a breech-bolt actuating spring, to be hereinafter described.

40 A breech-bolt 46 is mounted for recipro- cating movement in the breech-bolt chamber 41, this bolt being preferably round in cross section and having friction cheeks 47 extending from opposite sides through slots 48 in the receiver, these cheeks being roughened to 45 afford a gripping surface by means of which the breech-bolt may be manually moved backwardly. A groove 49 is formed in the upper side of the breech-bolt to complete the breech-bolt actuating spring chamber herein- 50 before referred to, a breech-bolt actuating spring 50 being located in this chamber and thrusting with its forward end against the end of the groove 49 and with its rear end against a plug 51 secured in the receiver, 55 this plug having a supporting rod extending within the spring. A breech-bolt lock 52 is slidably mounted in the breech-bolt, being movable therein in a radial direction and having a slot 53 through which a firing pin 60 54 extends. The outer end of this lock rests in contact with the breech-bolt unlocking dog 42, and when said dog moves the stop inwardly beyond the inner surface of the breech-bolt chamber, then the breech-bolt is 65 free to move independently of the receiver.

A lock plunger 55 is seated upon a spring in a recess in the lock, as shown in Figure 6 of the drawings, and acts to force said lock into contact with the lever 42.

A firing pin supporting plug 56 is secured within the end of the breech-bolt, this plug having a recess 57 to receive a collar secured to the firing pin 54, as shown in Figure 1 of the drawings. The mouth of this recess is closed by a collar 58 within which the firing pin is freely movable, a firing pin spring 59 thrusting against said collar and acting to force the firing pin to the rearward limit of its play when not held in the opposite position by the hammer 18. A safety lug 60 80 extends from one side of the firing pin in position to be partially located in the slot 53 in the breech-bolt lock, this lug being of such length that it will strike the side of said lock underneath the slot when the latter 85 is in its inward or unlocked position. Consequently when the breech-bolt is unlocked from the receiver the firing pin cannot be forced forward far enough to explode a cartridge, and it can move forward sufficiently 90 to do this only after the lock 52 is in its locked position. The trigger bar 15 extends backwardly past one side of the magazine chamber and its rear end is provided with a sear actuator 61 and a knock-off 62, the latter extending into a knock-off recess 63 in the under side of the receiver, the contacting portions of the recess and knock-off being beveled to permit disengaging movement of said parts. The trigger bar is forced to an 100 upward position by means of a spring pressed plunger 64 located in the frame and thrusting upwardly against said bar. A breech-bolt stop 65 projects from the side of the breech-bolt into a breech-bolt controlling slot 66 formed in the side of the receiver, 105 said stop, by contact with the end of said slot, limiting and determining the endwise movement of the breech-bolt. This slot 66 also serves as an outlet opening for spent shells which are extracted from the barrel, as the breech-bolt is moved backwardly and comes in contact with an ejector in a manner that will be readily understood by those skilled in the art, and which extracting and 110 ejecting elements are, therefore, not illustrated and described herein.

The operation of my improved firearm hereinabove described is as follows:

115 It being assumed that a loaded magazine is in place in the magazine chamber 11, and the parts being in the position shown in Figure 1, the breech-bolt may be moved backwardly by the operator gripping the cheek pieces 47 and exerting force in a backward direction. When the breech-bolt has uncovered the upper cartridge in the magazine, the magazine spring forces the topmost cartridge out of the magazine into the line of movement 120 of the breech-bolt in a manner readily un- 125

derstood by those acquainted with firearms of this class, and when the manual force is released from the breech-bolt it will move forward under the tension of the spring 50 and force a cartridge into the opening in the barrel. This backward movement of the breech-bolt also cocks the hammer 18. The trigger being now pulled, the trigger bar 15 and the sear actuator thereon, will engage the actuating finger 25 of the sear and disengage the sear from the hammer, and the latter will be thrown forcibly down by the spring 21 striking the firing pin 54 and driving it forward to explode the cartridge. The force of the recoil caused by the firing of the pistol will operate to move the receiver, and the breech-bolt that at this time is locked to the receiver by the lock 52, backwardly until the retaining recess 37 is located opposite the lock 27 when the latter moves under the force of the spring 28 into the recess 37, to temporarily hold the receiver from forward movement. In this backward movement of the receiver the dog 42 engages the back edge of the groove 32 and is forced upwardly thereby moving the lock 52 upwardly and releasing the breech-bolt from locked engagement with the receiver. The breech-bolt is now free to move backwardly under the momentum gained by the forces of the gases generated in the breech of the barrel and the consequent initial recoil above mentioned, and, in this backward movement, the hammer is cocked in the same manner as hereinbefore described with respect to the manual movement of the breech-bolt, and the topmost cartridge is, in the manner hereinbefore described forced into the breech in the barrel.

When the receiver moves back as hereinabove described, the beveled front edge of the recess 63 encounters the knock-off 62 and forces the trigger bar and the sear actuator thereon downwardly so that the latter is out of the path of movement of the actuating finger 25 and the latter is, therefore, free to move forward under the force of the sear spring, the sear being thus free to assume a position to catch and hold the hammer when it is moved to its cocked position by the backward movement of the breech-bolt. When the breech-bolt moves to its closed position under the force of the spring 50, the beveled edges of the retaining recess 37 and the stop 27 will cause the stop to be released from the recess and the receiver will move forward to its initial position, or position of rest, the parts now being in their proper position for a repetition of the firing operation above described.

It will be noted that the breech-bolt is uniform in diameter and round, with the exception of the roughened cheeks, from end to end, and that the groove for the

breech-bolt actuating spring may be readily milled, so that the breech-bolt is comparatively inexpensive to make and the breech-bolt lock likewise being round may be readily produced upon an automatic machine. This breech-bolt lock is so located that it will not pass out of the breech-bolt chamber in the backward movement of the breech-bolt.

The recess 63 is slightly wider than the knock-off 62 to enable the trigger bar to be moved sufficiently to disengage the sear from the trigger. The sear shaft, sear and actuating finger 25, in fact, constitute the sear, said finger being the sear tail. A projection 67 on the lower end of the hammer is formed to close the mouth of the well 20 and thus prevent entry of objectionable matter within said well. The edges of the slot 66 are beveled on the inner surface as to the top edge and on the outer surface as to the bottom edge to provide an opening extending in a diagonally downward direction, so that the spent shells, when they are drawn from the barrel and ejected, are caused to travel in a diagonally downward direction from the pistol.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

I claim:

1. A firearm including a frame, a receiver movably mounted on the frame, said parts having a chamber for the receiver actuating spring, an actuating spring located in said chamber, a controlling slot and retaining recess located in one of said parts (frame or receiver); a locking bolt located in the other part to engage said slot and recess, a breech-bolt movably mounted on the frame, and firing mechanism to actuate said breech-bolt.

2. A firearm including a frame having a groove therein, a receiver movably mounted on the frame and closing the top of said groove and having a lip closing the end of the groove, a spring located in said groove, a controlling slot and retaining recess located in one of said parts (frame or receiver), a locking bolt located in the other part to engage said slot and recess, a breech-bolt movably mounted in the receiver, and firing mechanism to cause operation of the breech-bolt.

3. A firearm including a frame having a recess in its upper edge at the crosswise center thereof, a hammer pivotally mounted on the frame, a sear located in said recess to engage the hammer, a shaft supporting the sear and projecting through the wall of and

beyond said recess, a sear tail secured to said shaft and located in a slot in the side of the frame separated by a wall from said recess, a receiver supported on the frame, and other parts of the firing mechanism supported on the receiver to be actuated by the movements of said hammer.

4. A firearm including a frame having a slot therein, a receiver movably mounted on the frame and having a hole therein and a slot opening out of said hole and in line with the slot in the frame, firing mechanism including a breech-bolt movably mounted in the receiver, a breech-bolt lock mounted in the breech-bolt and having a slot opening to the upper end thereof to receive a firing pin, and an unlocking dog pivotally mounted in the slot in the receiver and projecting into the slot in the frame and underlying and supporting said breech-bolt lock, said unlocking dog being shaped to engage the end of the slot in the frame to move the breech-bolt lock upwardly out of the hole in the frame and thus unlock the breech-bolt.

5. A firearm including a frame, a receiver movably mounted in the frame, and firing mechanism including a breech-bolt movably mounted in the receiver and having a hole extending crosswise thereof, a breech-bolt lock having a slot opening to the upper end thereof to receive said firing pin, and a plunger located in a recess in the upper end of the breech-bolt lock and thrusting against the upper wall of the receiver to force the

breech-bolt lock into locked engagement with the receiver.

6. A firearm including a frame, a receiver supported on the frame, and firing mechanism including a breech-bolt with an opening therein counterbored for a portion of its length, a plug closing said opening and having a recess in its inner end, a firing pin projecting through the breech-bolt and through said recess to form one wall of a chamber within the breech-bolt, mechanism located within said chamber, a collar surrounding the firing pin and seated against the shoulder of said counterbored opening to close said recess, a collar secured to the firing pin, and a spring secured between said collars to force the firing pin backwardly.

7. A firearm including a frame, a receiver supported on the frame, and firing mechanism including a breech-bolt with an opening therein counterbored for a portion of its length, a collar seated against the shoulder at the bottom of said counterbored opening and forming one wall of a chamber within the breech-bolt, mechanism located within said chamber, a plug closing the opening into the breech-bolt and securing said collar in place, a firing pin extending loosely through said collar and plug, a collar located on the firing pin, and a spring located between said collars to force the firing pin backwardly.

GRANT HAMMOND.
